UNITED STATES PATENT OFFICE.

WILLIAM N. WEST, OF DETROIT, MICHIGAN.

COMBINED BED AND COUCH.

SPECIFICATION forming part of Letters Patent No. 689,261, dated December 17, 1901.

Application filed November 30, 1900. Serial No. 38,110. (No model.)

To all whom it may concern:

Be it known that I, WILLIAM N. WEST, a citizen of the United States, residing at Detroit, county of Wayne, State of Michigan, 5 have invented a certain new and useful Improvement in a Combined Bed and Couch; and I declare the following to be a full, clear, and exact description of the invention, such as will enable others skilled in the art to 10 which it pertains to make and use the same, reference being had to the accompanying drawings, which form a part of this specification.

My invention relates to the combination of 15 folding beds and couches; and it consists in the combinations and arrangements herein-after specified and claimed.

In the drawings, Figure 1 is a perspective view of the framework of a combined folding 20 bed and couch constructed in accordance with my invention. Fig. 2 is an end view with certain portions broken away in order to show upholstering and the location of the bed, the dotted lines showing the outline of the bed 25 when arranged to be used as such. Fig. 3 is a detail view of one of the supporting-legs and the manner of attaching it to the frame.

Similar letters refer to similar parts.

In the drawings, A is a rectangular frame 30 which forms the basis of the couch and supports the front of the bed-frame when that is in position to be occupied as such, as shown in Fig. 1. The frame A is supported in front by legs A' A'. These are preferably fixed to 35 the frame and may be in turn supported on casters. The rear of the frame A is supported by broad supports B B, which in turn may also be supported on casters. These are fixed to the frame A and extend somewhat to the 40 rear of it, the extension corresponding in width to the width of the end pieces C C of the bed-frame.

D is the bed-frame, which contains and supports the mattress and bedding in the usual 45 manner.

The bed-frame is made up of the side pieces d' d' and the end pieces C C, together with such cross-supports as may be necessary.

The rear portion of the bed-frame is supported upon swinging legs E E, which are pivoted at the upper ends by hinges having

horizontal pivots in line with C at c. These are shown in detail in Fig. 3.

The front portion of the bed-frame is supported by the couch-frame A and pivoted at 55 b b to the upper part of the broad legs B B. As shown in Fig. 2, the bed-frame is elevated, so as to occupy a longitudinal upright position. The under side of the bed-frame is preferably upholstered, as shown at F, and forms 60 when in the position shown in Fig. 2 the back of the couch, which couch also may be upholstered, as shown in Fig. 2 at G.

H represents the bed, shown by breaking away a portion of Fig. 2, and this may be 65 supported in any convenient manner when the bed is elevated in the position shown in Fig. 2 by the use of straps or any other retaining means, all of which are familiar.

In order that the edges of the bed may not 70 be unduly high, the rails or side pieces d' d' are divided, the upper portion J J being hinged to a lower portion or the rail proper and being adapted to turn outwardly and downwardly, as shown upon the right-hand side 75 of Fig. 1, or to be turned upwardly, as shown at the left-hand side. The supports E E by virtue of the manner in which they are arranged do not swing loosely, but only swing 80 in a longitudinal direction with the bed, and therefore are never in the way when the bed is raised, as shown in Fig. 2. They are then swung in under the rails d' d' and retained by hooks.

It is obvious from the foregoing description, 85 the proper bedding and upholstering being supplied, that the device constitutes a combined bed and couch, the bed being shown (when the necessary bedding is supplied) in Fig. 1 and the couch in Fig. 2, and that all 90 that is necessary to transform or arrange the apparatus to utilize the bed is to turn the elevated portion of the back of the couch downwardly and bring the bed-upholstered faces together, as shown in dotted lines in Fig. 2, 95 and detach the legs E E from their hooks or supports, when they fall down to the floor and form the rear support for the bed-frame. While in this position the bed is as solid and rigid upon the floor as any bed-frame could 100 be that had no tendency whatever to overturn. Elevating the supports E E, the bed

can be raised to an upright position upon the pivots *b b* and, if desired, crowded up against the wall, thereby narrowing the space which it occupies and leaving only the couch for its appropriate use.

Having thus described my invention, what I claim is—

In a combined couch and bed, the combination of a frame A constructed to form the seat portion of a couch, a support B at the rear and at each end of the frame A, a frame D constructed on one side to form the back of a couch and on the other side to form a bed, the frame D being pivoted between the supports B substantially midway its ends adjacent to the upper part of the couch so that

it shall be balanced in turning, the frame D being so pivoted that its back-forming side shall turn over upon the seat-forming portion of the frame A, with its bed-forming surface 20 upward and its outer edge adjacent to the outer edge of the frame A, and legs E hinged to the frame D near its lower inner edge so as to fold against said frame, substantially as described.

In testimony whereof I sign this specification in the presence of two witnesses.

WILLIAM N. WEST.
